UNITED STATES PATENT OFFICE.

PETER SANTURELLO, OF COLUMBUS, OHIO.

HAIR-CURLING APPARATUS.

Application filed May 7, 1926. Serial No. 107,489.

My invention relates broadly to a hair curling apparatus and has to do particularly with the provision of a device for winding hair upon a mandrel and for simultaneously covering such hair with a tape.

In the past, in the permanent waving of hair, it has been the practice to secure a mandrel to a lock or bunch of hair adjacent the scalp by means of a piece of string or the like and to then wind or coil the hair by hand about the mandrel and secure the remote ends thereof to the mandrel by a second piece of string. The hair so wound about the mandrel was then covered by a spirally wrapped tape and then subjected to heat. This process is not only laborious, complicated and slow but it involves the use of various tools for tensioning the hair upon the mandrel, which is usually provided with a ratchet mechanism for securing the hair in taut position. Also the winding of the hair and tape requires considerable skill on the part of the operator and uniform and satisfactory results are not always obtained.

My invention provides, among other things, mechanism for securing a mandrel to the hair without the use of strings, et cetera; mechanical means for winding or coiling the hair upon the mandrel and for simultaneously covering such hair with a spirally wound tape; and means for stretching and overlapping the successive spirals of hair and tape to obtain tightly and uniformly wound curl's of hair.

The principal object of my invention is the provision of means whereby the curling and tape wrapping operations may be rapidly accomplished without damaging the hair or requiring the services of a skilled operator.

Another object of my invention is the provision of a positive, effective and easily manipulated gripping and locking device for attaching the mandrel to a lock of hair adjacent the scalp.

A further object of my invention is the provision of a device for mechanically winding hair about a mandrel in a manner which ensures overlapping of the successive spirals and produces deep, uniform, and equally tensioned curls.

A still further object of my invention is the provision of mechanism for wrapping a tape around the hair upon the mandrel and for performing this tape winding operation

simultaneously with the hair winding operation.

Another object of my invention is the provision of means for securing the wound hair and tape upon the mandrel during the subsequent dampening and heating operation.

Still another object of my invention is the provision of means for securing the mandrel and heating apparatus together during the steaming of the hair.

Other important features of my invention will appear as the description progresses and will be more particularly defined in the appended claims.

The various objects of my invention may be obtained by the embodiment illustrated in the accompanying drawings wherein similar reference numerals designate corresponding parts in the several figures and wherein—

Figure 1 is a side elevation of a curling mandrel showing my improved hair gripping and locking device attached thereto;

Figure 2 is an end elevation of the hair gripping and locking device shown in Figure 1;

Figure 3 is a perspective view of the mandrel and gripping device shown in Figure 1 with parts disassembled and showing the manner of securing the different parts in operative relation, and the spirally recessed plates which co-act to attach the mandrel to a lock of hair;

Figure 4 is a perspective view of the device employed for winding the hair and tape around the mandrel;

Figure 5 is a perspective view similar to Figure 4 but showing the opposite side of the winder and particularly the slot through which the tape enters;

Figure 6 is a perspective view of the tape containing shell and parts for attaching it to the winder;

Figure 7 is a perspective view of the winder and tape container in assembled relation;

Figure 8 is a perspective view of one form of spring clip for securing the mandrel within the heating apparatus;

Figure 9 is a perspective view showing the mandrel, hair winder and tape container in assembled relation and a lock of hair secured in the gripping head preparatory to the hair and tape winding operation;

Figure 10 is a perspective view similar

to Figure 9 showing the hair partially wound upon the mandrel and the tape covering the wound hair;

5 Figure 11 is a side elevational view showing the hair and tape winding operations completed, the tape container having been removed from the winder and the mandrel secured within the heating apparatus;

10 Figure 12 is a perspective view showing a modified winder;

Figure 13 is a perspective view showing the same winder as is shown in Figure 12 but with parts in dotted lines to show the interior thereof;

15 Figure 14 is a side elevational view showing in particular an adapter whereby my novel mandrel and winder may be fitted to heaters of different sizes and designs;

20 Figure 15 is a side elevational view, partly broken away to show the interior of the adapter shown in Figure 14 and the spring clip for holding the mandrel in assembled relation therewith;

25 Figure 16 is a fragmentary sectional view taken on line 16—16 of Figure 15;

Figure 17 is a transverse sectional view taken on line 17—17 of Figure 16, and

30 Figure 18 is a fragmentary and partly sectional view showing a novel temperature indicator in association with the adapter illustrated in Figure 14.

35 In the drawings, one illustrative embodiment of my invention is shown as comprising a mandrel 1 which is preferably of hollow cylindrical construction but which obviously may have any desired cross sectional shape and dimensions of any convenient magnitude. Attached to one end of the mandrel 1, I have provided a gripping and 40 locking device for securing the mandrel to a lock of hair in close proximity to the scalp.

45 This gripping device comprises the superimposed plates 2 and 3 which are preferably co-axially mounted and formed with the opposed spiral recesses or slots 4 and 5 for a purpose which will hereafter appear. The lower plate 2 may be formed with a downwardly depending flange 6 carrying a stop 7, a centrally disposed externally threaded 50 projection 8, adapted to interfit with the internally threaded end 9 of the mandrel 1, and an oppositely extending internally threaded post 10 forming a bearing portion for the upper plate 3. The upper plate 3 may be formed with a flange 11 which encloses part of the flange 6 of the plate 2 when the two plates are superimposed, and may also be provided with lugs 12 and 13 which abut the stop 7 formed on the flange 6 of the plate 2 when the upper plate is revolved or oscillated about the post 10.

55 The two plates 2 and 3 may be secured in contacting relation by means of a screw 14 which engages a threaded socket in the post 10. The head of screw 14 is preferably

countersunk or positioned in the cup 15 formed on plate 3 and a resilient washer or spring 16 may be interposed between the cup 15 and the head of screw 14 for increasing the friction between plates 2 and 3. 70 With the construction just described, the plates 2 and 3 are revolvable or oscillatable with reference to each other and they remain in any relative position to which they have been revolved or oscillated. When in 75 the position shown in Figures 1 and 2, a lock of hair may be inserted in opening 17 and either plate revolved relatively to the other by turning plate 3 by means of projection 18 or by turning mandrel 1 to which 80 the plate 2 is secured. The plates 2 and 3 are arranged in overlapping relation and the screw 14 countersunk or encased by cup 15 to prevent the hair from becoming entangled or fast in the device when in use. 85

90 In the use of the gripping device just described, when a lock of hair on the scalp has been segregated and positioned in the opening 17, one of the plates 2 or 3 is revolved or turned with relation to the other and the spiral slots 4 and 5 progressively eclipse the opening 17 until the mandrel is 95 tightly, secured to the hair, as shown in Figure 9. The friction between plates 2 and 3 will be sufficient to prevent loosening of the plates or disengagement of the hair during succeeding operations. The opening 17 first completely encloses the hair and then becomes progressively smaller as the plates 2 and 3 are revolved, and my invention thus provides means for accommodating 100 different sized locks or bunches of hair.

105 The winding device for wrapping or coiling the hair around the mandrel 1 comprises a hook-like outwardly extending finger 19, a relatively narrow helical slot 20 which communicates with a comparatively larger opening 21 and an internally enlarged cup portion 22 which is formed in continuation of the main body portion 23. The centrally bored main body portion 23 of the winder may be provided with the oppositely disposed ribs 24 and 25 and a projection 26 for a purpose to be hereafter explained. 110 The main body portion 23 is also preferably formed with the externally threaded spring segments 27 that are separated by slots 28 and carry a knurled nut 29 which is adapted to constrict the opening 30 when screwed onto the slightly tapering segments 27 and 115 so hold the winder in any desired position upon the mandrel. The enlarged cup portion 22 is designed to contain the lock or bunch of hair 31 (Figure 10) which is carried thereinto by the finger 19 and helical slot 20, and the lip 32 functions to smooth and stretch the hair as it is being wound. The helical slot 20 and opening 31 are preferably proportioned to carry the hair into the cup portion 22, stretch it and overlap 120 125 130

the successive spirals to form uniform, deep and properly tensioned curls or coils upon the mandrel.

One of the principal objects of my invention is the provision of means for simultaneously wrapping the hair being wound upon the mandrel with a tape. Therefore, I have provided a tape container which is adapted to be removably attached to the winder. This tape container as best shown in Figure 6 comprises a shell 33 which is preferably provided with a central spindle 34 and a slot 35. The shell 33 is secured to a bracket 36 which has a substantially circular portion 37 and outwardly extending clamps 38, one of which is notched as at 39. This bracket is adapted to be attached to the winder in the manner illustrated in Figures 7, 9 and 10. By reference to these figures it will be seen that the clamps 38 are straddled over the ribs 23 and 24 of the winder and the bracket slid onto the winder until stopped by the dent 40 abutting against the main body portion 23 of the winder. When in this position the bracket may be revolved slightly with reference to the winder, whereupon the notch 39 will engage with the projection 26 and so effectually prevent the bracket from moving lengthwise of the winder during subsequent operations. When properly positioned, in the above described manner the slot 35 of the tape containing shell 33 will register with the tape slot 41 of the winder. The tape employed is preferably of cloth and wound in such a manner that a roll thereof may be slipped onto the central spindle 34 of the tape container 33 and its free end projected through the slot 35. The free end of the roll of tape 42 may be tapered or cut away as clearly shown in Figures 9 and 10. After the roll of tape has been positioned upon the spindle 34 and its free end threaded through slot 35, the bracket 36 may be attached to the winder and the free end of the tape passed through slot 41. When thus assembled and the winder slid onto the mandrel the device presents the appearance shown in Figure 9.

50 In operation, when the mandrel 1 has been secured to a previously segregated lock or bunch of hair adjacent the scalp by revolving or oscillating either of the plates 2 or 3 as previously described, the winder is slid into contact with the underside of plate 2; the hair engaged under finger 19 and the winder revolved whereupon the hair will be carried into the opening 21. Meanwhile the 55 end of the tape is held by the projecting end thereof until the first few spirals have been wound. The winding operation is best 60 shown in Figure 10 and by reference thereto, it will be seen that the edges of opening 21 and the lip 32 of the winder carry the hair 65 31 around the mandrel, and that the slot 41

carries the tape around the hair. As the winding continues the winder is progressively slid downward along the mandrel and the hair is wound and wrapped with tape in a uniform and systematic manner. The hair is also stretched, smoothed and spread and the successive spirals overlapped by the turning of the winder. The spirals of hair and tape are also overlapped so that parts of the spirals of hair are enclosed between the successive layers of tape and parts are pressed directly between the mandrel and overlying tape. The winding operation is continued until about all of the hair and tape have been wound around the mandrel, whereupon the downward movement of the winder is preferably discontinued and the winder simply revolved until all of the ends of the individual hairs have disappeared into the cup portion 22 and all of the tape has been unwound from the spindle 34. When this has occurred the winder may be forced against the wound hair and tape to compact it lengthwise, the winder being preferably simultaneously revolved to give the hair and tape a final stretching; then the nut 29 may be tightened to secure the winder in place upon the mandrel during succeeding operations. The appearance of the device during an intermediate stage of the hair and tape winding is illustrated in Figure 10. During the winding operation, the clamps 38 serve as a convenient grip for the fingers. After the hair and tape have been wound upon the mandrel the bracket 36 may be removed from the winder and when this has been done the device appears as illustrated in Figure 11. It will be understood that the ends of the hair and tape are securely held within the cup portion 22 of the winder and thereby prevented from loosening or unwinding during subsequent operations.

When the hair has been wound on the mandrel as above described, it is ready for the heating or steaming operation. The roll of tape 42 may be dampened with the hair treating liquid prior to insertion in the shell 33 and again dampened after the winding has been completed the exact time of dampening somewhat upon the preference of the user. For the purpose of applying heat to the hair and tape any desired type of heater may be employed and I have diagrammatically shown an electric heater in Figure 11 which comprises a tube 59 and a resistance element container 51. The mandrel may be positioned in this heater as shown in Figure 11 and secured therein by means of the spring clamps 52 and 53 which engage with the groove 54 around the end of the mandrel. These spring clamps are secured to a plate 55 and are provided with portions 56 which engage with the walls of the tube 50. Thus the mandrel is securely but removably held within the heater and the plate 55 together

with the plate 2 of the gripping head forms a seal to prevent escape of steam during the heating. The spring clamps may be easily adjusted longitudinally of the tube 50 to accommodate mandrels of different lengths and different types of heaters.

When the heating and steaming operation has been completed it is only necessary to remove the mandrel from the heater by 10 disengaging the groove 54 from the spring clips 52 and 53; loosen the lock nut 29; slide the winder out of contact with the hair and tape; unwind the tape from the hair; and then release the hair from the gripping device. It will be noted that the entire apparatus may be readily disassembled for 15 cleaning or other purposes and when the different parts are assembled their engaging portions are all in opposition so that revolving or 20 manipulating one part will not loosen or disengage other parts which have been previously secured together.

In Figures 14, 15, 16 and 17 is illustrated a novel arrangement whereby my mandrel 25 may be adapted for use in heating elements of different sizes and designs. There are on the market a great many different sized heaters for steaming the hair wound upon a mandrel, and these heaters have central 30 openings of different sizes and are of widely varying length. Therefore, I have provided a 35 adapter comprising a tube 80 having a flared end 81 and its other end fitted with a removable cap 82. Slidably mounted on the 40 tube 80 is a collar 83 having a tapered portion 84 and provided with a set screw 85 whereby the said collar may be secured in any 45 desired position upon the tube 80. The tube 80 may be inserted through the central opening 87 of the particular heater 86, the collar 83 and cap 82 being removed at this time and then the collar 83 slid onto the tube and 50 secured in place by the set screw 85. The cap 82 together with the depending flange 55 of the lower plate of the hair gripping device will prevent escape of steam during the heating. It will be noted that the tube 80 is 60 of sufficient length to fit most any heater and that the flared end 81 together with the tapered portion 84 of the collar 83 adapt the tube to heaters having different sized 65 central openings.

Within the tube 80 I have provided a 70 spring clip 90 having resilient tongues 91 and 92 which are provided with corners 93 intended to engage the inner wall of the tube 80 in such a manner as to prevent sliding of the clip 90 as the end groove 54 of the 75 mandrel is inserted between the resilient tongues 91 and 92. This spring clip forms a convenient means of removably securing the mandrel within the heating apparatus and together with the tube 80, which is preferably formed from a metal having a high 85 thermal conductivity, provided means for

adapting my mandrel and winding apparatus to the different types and sizes of heaters.

In Figure 18, I show a temperature indicating device which may be employed in 70 association with the adapter tube 80 or in direct association with any other type of heater. In the heating or steaming of hair wound upon a mandrel it is the practice to expose the hair for a certain definite time 75 to the action of the heat, and this practice is objectionable because variations in the strength of the current passing through the resistance element and variations in other factors cause the hair to be heated either 80 too much or too little during the time the hair remains within the heater. Accordingly I have provided a temperature indicating device 100 which may be removably positioned within an opening 101 of a cap 102 85 designed to engage with the end of adapter tube 80 or with the end of the particular heater with which it is employed. This temperature indicator may comprise a thermometer 103 suitably graduated as at 104 90 and having its bulb portion 105 which is preferably encased by a metal sheath 106 positioned within a relatively large chamber 107 formed in the cap 102. In using this device the operator may know the exact temperature to which the hair is being subjected and so either prolong or shorten the ordinary 95 heating time as found necessary to obtain the best results. Another way of using this device is to ignore the usual time period and 100 simply heat the hair until the thermometer indicates a certain predetermined temperature.

From the foregoing description it will be apparent that I have provided a device 105 which may be employed for curling hair in a minimum time and in a uniform and systematic manner. My invention also, properly tensions the hair, avoids the use of 110 strings and the like and performs simultaneously the two ordinarily separate operations of hair winding and taping. It will furthermore be apparent that my novel adapter makes possible the use of my mandrel and 115 winder with heaters of different sizes and designs and that the temperature indicating device makes possible a very accurate control of the heat to which the hair is subjected.

Having thus described my invention, what 120 I claim is:

1. In a device of the class described, the combination of a mandrel, a winder and a tape container removably secured to said winder.
2. The method which comprises winding hair upon a mandrel and simultaneously covering such hair with a tape.
3. The method which comprises securing a mandrel to a lock of hair, curling said 130

lock of hair around said mandrel and simultaneously covering the hair so curled with a tape.

4. A device of the class described, comprising in combination, a mandrel, rotatable means for wrapping hair around said mandrel and means for covering the hair so wrapped, around said mandrel with a tape.

5. A device of the class described, comprising a winder and a tape container attached to said winder.

6. A device of the class described, comprising a mandrel, a winder adapted to wrap hair around said mandrel, a tape, and a slot formed in said winder for wrapping said tape around said mandrel.

7. A device of the class described, comprising a mandrel, hair winding means revolvably and slidably mounted upon said mandrel and a tape container removably attached to said winder, said tape container embodying means for supporting a roll of tape.

8. A device of the class described, comprising a mandrel, a slotted hair winder revolvably and slidably mounted upon said mandrel and means attached to said winder and adapted to support a roll of tape in proximity to the slot in said winder.

9. A hair winder for wrapping a lock of hair around a mandrel embodying means for covering the hair so wrapped with a tape.

10. In combination, a mandrel, a revolvable winder for wrapping hair around said mandrel and means for wrapping a tape around said hair.

11. In hair curling apparatus, a mandrel, and a winding device comprising a cylindrical sleeve embodying a reduced end portion having slotted segments, said segments having frictional contact with the mandrel and permitting said device to slide longitudinally of said mandrel.

12. In hair curling apparatus, a mandrel, a winding device comprising a cylindrical sleeve embodying a reduced end portion

having slotted segments, said segments having frictional contact with the mandrel and permitting said device to slide longitudinally of said mandrel, and means adapted to engage said segments to lock said device upon said mandrel.

13. In hair curling apparatus, a mandrel, and a winding device comprising a cylindrical sleeve embodying an enlarged cup portion having a finger and a helical slot and a reduced end portion comprising slotted segments, said segments having frictional contact with the mandrel and permitting said device to slide longitudinally of said mandrel.

14. In hair curling apparatus, a tube adapted to contain a mandrel having a slideable movable means mounted thereon for positioning and securing the said tube within the central openings of heaters of various sizes.

15. In hair curling apparatus, a tube adapted to contain a mandrel having a slideably movable means disposed about the circumference thereof for positioning and securing the said tube within the central openings of heaters of various sizes.

16. In hair curling apparatus, a heater having a central opening, a tube, a mandrel mounted within said tube, and a slideably movable means disposed about the circumference of said tube for positioning and securing said tube within the central opening of said heater.

17. In hair curling apparatus, a heater having a central opening, a tube, a mandrel mounted within said tube, and a slideably movable means disposed about the circumference of said tube for positioning and securing said tube within the central opening of said heater, said tube containing a resilient clip for rigidly holding said mandrel.

In testimony whereof I hereby affix my signature.

PETER SANTURELLO.
